CABINET FOR FUEL GAS CYLINDERS

Mercer G. Farrar, Scarsdale, N. Y., assignor, by
mesne assignments, to Union Carbide and Car-
bon Corporation, a corporation of New York

Application September 22, 1932, Serial No. 634,288

4 Claims. (Cl. 248—225)

This invention relates to cabinets, particularly those for housing cylinders of fuel gas and the mechanism associated with such cylinders whereby gas is alternately delivered at a regulated pressure from such cylinders to a gas supply pipe. More specifically, the invention relates to a novel means whereby the change-over and pressure regulating devices may be more easily and quickly mounted on and removed from the rear wall of the cabinet.

The cabinets heretofore in use have been built to house two upright cylinders of fuel gas, and the change-over and pressure regulating devices have occupied space between and above the cylinders. Before or at the time the cabinet was installed, these devices were secured to the rear wall of the cabinet, as by fastening the pressure regulator to the cabinet wall by means of bolts or screws. At times it is advisable or necessary to remove these devices for inspection or repair, or to substitute a different pressure regulator, and in some instances to mount the devices in a different position in the cabinet.

Therefore, one object of this invention is to provide a novel means for quickly mounting a pressure regulator on a fuel gas cabinet without the use of any tools whatever so that it is firmly secured thereto, and may also be quickly and easily removed.

Other aims, objects, and novel features will appear in the following specification and the accompanying drawings, in which

Fig. 1 is a front view of a cabinet embodying this invention with the doors thereof open to show a pressure regulator, the change-over device, and accessory parts mounted therein;

Fig. 2 is a fragmentary view of the rear wall of the cabinet of Fig. 1, showing the arrangement of the attaching lugs;

Fig. 3 is a section along line 3—3 of Fig. 1, showing the form of one of the attaching lugs, and a part of a pressure regulator interfitting therewith;

Fig. 4 is a front view of one form of mounting bracket or support for a pressure regulator;

Fig. 5 is a side view of the mounting bracket shown in Fig. 4, showing a regulator mounted thereon;

Fig. 6 is a view of a pressure regulator having a mounting bracket as an integral part thereof;

Fig. 7 is a view showing one of a pair of plates adapted to be attached to the inner wall of the fuel gas cabinet and provided with a plurality of attaching lugs for use in place of those

formed integral with the cabinet as shown in Figs. 1 and 2.

Fig. 8 is a sectional view along line 8—8 of Fig. 7 showing the means for securing the mounting plate to the cabinet.

The broad idea of my invention comprises providing a fuel gas cabinet and a fluid pressure regulator with interfitting parts so constructed and arranged that the pressure regulator may be assembled to the fuel gas cabinet quickly and easily without the use of any tools whatever.

One example of the application of my invention is shown in the accompanying drawings wherein a fuel gas cabinet 10, constructed chiefly or entirely of sheet metal, is provided with a plurality of lugs 11 that are sheared from the rear wall thereof and pressed inward to give them a suitable form, such as V-shaped shown in Fig. 3. On the lugs 11, a bracket 12 is mounted that carries a fluid pressure regulator 13 and a change-over mechanism, such as valves 14, pressure gauge 15, inlet leads 16, and a suitable outlet conduit 17. Each of the leads 16 is provided with a coupling 18 by which it may be connected to cylinders A and B of liquefied or compressed fuel gas. Only one cylinder is ordinarily in service at a time, the other being kept in reserve, so that when one cylinder becomes empty, the change-over valves 14 may be operated, closing the lead 16 from the empty cylinder and opening the lead 16 connected with the full cylinder, after which the empty cylinder may be replaced.

The lugs 11, as shown in Figs. 1, 2, and 3 are sheared from the rear wall of the cabinet 10 in the area between the cylinders A and B and pressed inward far enough to extend some distance through suitable openings, slots, or recesses 19 in the mounting bracket 12, as shown in Figs. 3 and 4. Any suitable number of these lugs 11 may be provided, such as eight shown in the illustration and they may be arranged in any suitable way such as in aligned groups of two or more. The mounting bracket 12 is provided with two associated openings 19 in each corner thereof adapted to fit around the lugs 11 which project inward therethrough. The lugs are preferably of substantially the same size as the openings and when the regulator is mounted on the lugs the upper edges of the openings rest on the upper edges of the lugs. When assembled, the mounting bracket may be secured to the lugs 11 by any suitable means or retainers, such as pins 20 that are inserted or passed vertically behind or through the lugs 11 and in front of the mounting bracket 12. Four attaching pins 20 may be em-

ployed, or one pin may be used for each group of aligned lugs at each side of the mounting bracket, as shown in Fig. 1. When in place the pins hold the bracket firmly against the wall of the cabinet so that the regulator and associated devices are secured against movement or displacement.

The mounting bracket 12 is provided with a hollow boss 21 having an inturned flange 22 provided with openings 23 by which a pressure regulator 13 may be attached thereto by means of bolts 24. This mounting bracket may vary in form according to the type of regulator employed and the means for mounting it upon the plate. Also the mounting bracket 12 may be an integral part of the regulator 13 as shown in Fig. 6. Furthermore, the regulator 13 may be provided with feet having openings 19 therein, or the mounting bracket 12 may be of skeleton construction.

Under some conditions it is not desirable to form the lugs 11 integral with the rear wall 25 of the cabinet 10. In such case, the lugs 11 may be formed in a complementary pair of plates of the type shown in Fig. 7. These plates 26 may be of any suitable form and provided with openings 27 by which they may be bolted to the wall 25. The entire plate 26 may be on one plane or the portion containing openings 27 may be offset to provide space thereunder for jam nuts 29 to hold the attaching bolts 28 to the cabinet, as shown in Fig. 8.

Under some conditions it is desirable to provide means for mounting the regulator in either of two or more vertical positions or heights with respect to the cabinet 10. In order to accomplish this result the cabinet 10 or the plates 26 may be provided with two or more sets of lugs 11 as shown in Fig. 2 so located that the mounting bracket 12 may be inserted over one set when one position is desired and over another set when another position is desired. It is obvious, of course, that two or more complete sets of lugs may be provided or part of the lugs may be common to both mounting positions.

The mounting bracket 12, regulator 13, valves 14, gauge 15, and leads 16 are ordinarily shipped from the factory in assembled condition, and therefore this assembly may be mounted in cabinet 10 by placing the openings 19 in the mounting bracket over or around the lugs 11 of the cabinet 10 and then inserting pins 20 between lugs 11 and the mounting bracket 12. This operation may be performed quickly and easily without the use of any tools whatever and the regulator will remain securely attached to the cabinet until it is manually removed, which operation may be performed with equal facility to that of attaching.

While a preferred embodiment of my invention

has been illustrated and described, it will be understood that the lugs 11 may be of a different form from that shown and the means for mounting bracket 12 thereon may be altered to conform thereto. Also, other means for holding the bracket to the cabinet may be substituted for the pins 20. This and other changes may be made without departing from the range of the invention or the scope of the claims.

I claim:—

1. In a cabinet adapted to house two fuel gas cylinders in upright position and spaced apart; the combination of means for mounting a pressure regulator in the space between said cylinders, such means comprising a plurality of vertical rows of V-shaped lugs carried on the rear wall of said cabinet between said cylinders, a bracket fitting and supporting said regulator and having slots respectively fitting said lugs, and a plurality of devices each inserted through one row of 20 said lugs to hold said slots and said lugs in interfitting relation and said bracket on said wall.

2. In a cabinet for fuel gas cylinders, a plurality of lugs carried by said cabinet; a bracket provided with openings adapted to receive said 25 lugs and a boss adapted to receive a pressure regulator therein; and means adapted to retain said bracket on said lugs to secure said pressure regulator to said cabinet.

3. In a sheet metal cabinet for fuel gas cylinders, a plurality of groups of vertically aligned inwardly extending V-shaped integral lugs formed in the rear wall thereof; a bracket for a pressure regulator having a plurality of groups of aligned openings to receive said groups of aligned 35 lugs; and a retaining pin in each of said groups of aligned lugs in front of said bracket.

4. In a cabinet adapted to house two fuel gas cylinders in upright position and spaced apart, means for mounting a fluid pressure regulator on 40 the rear wall of said cabinet between the cylinders in such manner that said regulator may be removed and replaced without disturbing the cylinders in the cabinet, such mounting means comprising a supporting bracket for said regulator 45 fitting in the space between the cylinders and having two spaced vertical rows of slots; two similarly spaced vertical rows of lugs on said wall between the cylinders and projecting through said rows of slots, respectively; and two pins severally cooperating with said lugs and said bracket to hold the latter and the regulator thereon in position, each pin extending through a vertical row of lugs and being both insertable and removable through the space between the 55 cylinders without disturbing the latter.

MERCER G. FARRAR.
